UNITED STATES PATENT OFFICE.

ERNEST O. POHL, OF PHILADELPHIA, PENNSYLVANIA, ASSIGNOR TO HIMSELF, MAURICE A. MACKEY, AND CHARLES H. HENKELS, ALL OF PHILADELPHIA, PENNSYLVANIA.

CHANGEABLE SIGN AND ACTUATING MEANS THEREFOR.

No. 801,905.

Specification of Letters Patent.

Patented Oct. 17, 1905.

Application filed January 3, 1905. Serial No. 239,364.

To all whom it may concern:

Be it known that I, ERNEST O. POHL, a citizen of the United States, residing at the city of Philadelphia, in the county of Philadelphia and State of Pennsylvania, have invented certain new and useful Improvements in Changeable Signs and Actuating Means Therefor, of which the following is a specification.

My invention has relation to changeable signs for advertising and other purposes, and in such connection it relates more particularly to means for successively displaying in such changeable signs the sign, lettering, or other matter.

The principal objects of my invention are, first, to provide a changeable sign with a series of independent sign-plates adapted for the reception and display of advertising or other matter; second, to provide means for periodically displaying and removing each disconnected sign-plate in regular sequence, and, third, to provide means adapted to receive certain of the display sign-plates and to store the same for subsequent use.

My invention, stated in general terms, consists of a changeable sign and actuating means therefor, constructed and arranged in substantially the manner hereinafter described and claimed.

The nature and scope of my present invention will be more fully understood from the following description, taken in connection with the accompanying drawings, forming part hereof, in which—

Figure 1 is a vertical sectional view of periodically-changeable sign-plates arranged in suspended series and illustrating also in side elevation means for actuating and displaying certain of the sign-plates embodying main features of my invention. Fig. 2 is a side elevational view, partly sectioned, of a portion of a housing adapted to receive the sign-plates and of the actuating means therefor and illustrating, also in front elevation, a portion of the means for raising and lowering certain of the sign-plates and for bringing the same into and out of engagement with the raising and lowering means. Fig. 3 is a longitudinal sectional view of the housing, illustrating in top or plan view actuating means for the sign-plates and means for controlling the operation of the same. Fig. 4 is a detail view illustrating in side elevation a

shifting-lever and shifting-arms carried by the same and means for actuating the lever; 55 and Fig. 5 is a sectional view of a portion of the housing, illustrating in side elevation shelves or supports for the sign-plates and guides for a chain adapted to support and to raise and lower certain of the sign-plates. 60

Referring to the drawings, *a* represents a housing provided in the front wall *a'* thereof with openings *a²* and *a³* and at the top with a lid *a⁴*. As illustrated in Figs. 1, 3, and 5, adjacent to each side wall *a⁵* and *a⁶* of the 65 housing *a* are arranged partition-walls *b* and *b'*, provided with superposed shelves or ledges *c* and *c'*, the upper shelf *c* being provided with vertically-disposed extensions *c²* and *c³*, for a purpose to be hereinafter more fully described. The shelves *c* and *c'* serve to support two rows or series of disconnected signs. Each sign consists of an oblong strip or plate *d*, preferably of metal. At the upper end of each plate are provided blocks *d'*, carrying 70 rollers *d²*, normally engaging the shelves *c* or *c'*, as illustrated in Figs. 1 and 3. The blocks *d'*, preferably square in cross-section, serve when resting side by side to hold the plates or signs *d* a certain distance apart from each other and 75 to permit a predetermined number to be supported by each shelf *c* or *c'*. As illustrated in Fig. 1, in the present instance five signs *d* are supported by each of the shelves *c* and *c'*, while one sign opposite each series of five signs is supported by two endless sprocket-chains *e*, increasing the number of signs to 80 six in each row or series. Each of the sprocket-chains *e* is supported by guide-rollers *f*, two of which by means of brackets *f'* are secured 85 to the bottom of the housing *a* and another one and a sprocket-wheel *m'* by similar brackets *f'* to a partition-wall *g*, arranged above the upper series of signs *d*. To prevent sidewise movement of the chains opposite the rows of signs, 90 the same are guided in grooves *b²*, preferably arranged in the partition-walls *b* and *b'*, as illustrated in Figs. 1 and 3. Certain of the links *e'* of the sprocket-chains *e*, in the present instance each fifth link *e'*, is provided with 95 a projection or bracket *e²*, which being indented forms a seat for the roller *d²* of a sign-plate *d*, holding the same securely in position thereon. As illustrated in Fig. 1, 100 the sign-plate *d*, the greater portion of which is visible through the opening *a³* of the hous-

ing a , is supported by the sprocket-chains e , while the sign-plate d , visible through the opening a^2 , is supported by the lower shelf c' . In order to change the sign-plates opposite the openings a^2 and a^3 and to expose other sign-plates before the same, it is necessary to shift the upper sign-plate carried by the sprocket-chains e onto the upper shelf c and at the same time to shift the sign-plate d , carried by the lower shelf c' , onto the brackets e^2 of the chains e . By the shifting of these sign-plates the last of the upper series of plates at the right-hand side of Fig. 1 is shifted by the movement of the plates thereon onto the bracket e^2 of the chains e , while the last sign-plate of the lower series of plates at the same time is shifted onto the lower shelf c' . To both chains e are now imparted a movement from left to right in Fig. 1, by means of which the plate in front of the lower series of plates is raised and the plate in rear of the upper series of plates is lowered to change their positions with respect to the suspended series of said plates.

25 The preferred mechanism for shifting the sign-plates d and for actuating the chains e and the plates carried by the same is as follows: At each end of the housing a and pivotally secured at the point h' to the partition-walls b and b' thereof is arranged a lever h , having laterally-extending arms h^2 and h^3 , the bent end h^4 of each of which passes through openings a^4 , arranged in the housing a and terminating, respectively, in front and in rear of each of the series of plates. At the upper end of each of the levers h , hereinafter called "shifting-levers," is arranged a slot h^5 , which is engaged by a crank-arm i^5 , secured to the end of a shaft i , carried by standards i^6 , supported by the partition-wall g . The partition-wall g also serves to support two concentric bevel-gears k and k' , connected with each other, of which the outer gear k' is provided with teeth arranged in a semicircle, leaving the other half, k^2 , thereof toothless. The inner bevel-gear k meshes with a bevel-gear l , secured to a shaft l' , and the outer gear k' meshes alternately with a bevel-gear i^3 , fixed to the shaft i , and with a bevel-gear i^4 , loosely mounted thereon. 45 To the bevel-gear i^4 is rigidly secured a gear-wheel i^5 , and both wheels are held in position on the shaft i by collars i^6 , secured to the same. The gear-wheel i^5 meshes with a gear-wheel m^2 , rigidly secured to a shaft m , which 55 at its ends carries the sprocket-wheels m' , actuating the endless chains e . When the shaft l' by means of the crank-arm i^5 or by any other suitable means (not shown) is rotated, the movement thereof is transmitted by the 60 bevel-gear l to the bevel-gears k and k' , which are rotated in the direction indicated by the arrow in Fig. 3. The outer bevel-gear k' being first brought into engagement with the bevel-gear i^3 rotates the shaft i , which by means of 65 its arms i^5 oscillates the shifting-levers h on

their fulcrum point h' . The shifting-arms h^2 and h^3 , carried by the shifting-levers h , arranged at each end of the housing a , are now moved into the housing from opposite sides and by respectively engaging the blocks d' of the sign-plates d , supported by the chains e , shift the same onto the shelves c and c' . By these movements the last sign-plate of the upper series of plates and the first sign-plate of the lower series of plates are shifted onto the brackets e^2 of the chains e . By the further rotation of the bevel-gear k the bevel-gear k' is brought out of engagement with the bevel-gear i^3 , driving the shaft i , which now comes to a standstill and into engagement with a bevel-gear i^4 , while the toothless portion k^2 thereof moves inactive below the bevel-gear i^3 . The bevel-gear i^3 and shaft i during their rotation have described a complete revolution, by means of which the shifting-arms h^2 and h^3 are first moved forward and then backward into their normal position, as illustrated in Figs. 1 and 3. The bevel-gear i^4 being now actuated by the bevel-gear k' rotates the shaft m , and sprocket-wheels m' , through the intervention of the gear-wheels i^5 and m^2 , affording a complete revolution thereof. By this movement of the sprocket-wheels m' the chains e are moved forward for the distance of five links e' , which in the present instance is sufficient to raise the sign-plate of the lower series of plates carried and held by the same opposite the opening a^2 of the housing and to bring the same opposite the opening a^3 of the housing and at the same time lower the sign-plate d of the upper series of plates and to bring the same into alinement with the lower series of plates. The sign-plate d , previously visible through the opening a^2 , is now visible through the opening a^3 , and a plate of the lower series of plates and previously covered by the raised plate is now visible through the opening a^2 , the shifting of all plates and the simultaneous raising and lowering of two plates being continuous in regular sequence and in the manner hereinbefore described until all the plates have been displayed through the openings a^2 and a^3 of the housing a . After this the cycle in the plate-display commences anew. During the raising and lowering of the sign-plates d the rollers d^2 thereof abut against the shelf extensions c^2 and c^3 , respectively, of the upper shelf c and against the side walls a' and a'' of the housing a , as will be readily understood in connection with Fig. 3. The shelves c and c' are provided with raised end portions c^4 , which hold the rollers d^2 securely in position during the respective raising and lowering of two plates, as hereinbefore fully explained.

The sign-plates d being independent of and disconnected from each other and the shifting-arms h^2 and h^3 , as well as the chains e , the ready removal and replacement of said sign-plates by others are permitted thereby.

Having thus described the nature and ob-

jects of my invention, what I claim as new, and desire to secure by Letters Patent, is—

1. In a changeable sign, a housing having partition-walls, chains having projections arranged therein, superposed shelves carried by said walls, sign-plates arranged in series supported by said shelves and by the projections of said chains, oscillating means supported by said walls and having arms supported by said housing, and means adapted to actuate said oscillating means to bring said arms alternately into and out of engagement with the sign-plates in series.

2. In a changeable sign, a housing having partition-walls, guides formed therein, chains having projections passing therethrough, superposed shelves carried by said walls, sign-plates arranged in series and having rollers supported by said shelves and by the projections of said chains, an oscillating lever connected with each of said walls, arms connected with said levers and passing through said housing to engage the series of sign-plates from opposite sides, and means adapted to actuate said oscillating means to move the series of signs in opposite directions to each other.

3. In a changeable sign, sign-plates arranged in series and disconnected from each other, blocks for holding the sign-plates a certain distance apart in each series, superposed shelves and endless chains coöperating to sup-

port the series of signs, oscillating levers having an arm at each end engaging the signs supported by the chains to shift a sign of each series onto a shelf and from the shelf another sign back onto the chains, and means for successively actuating said arms and chains to transfer the signs from one series to the other.

4. In a changeable sign, sign-plates arranged in series and disconnected from each other, blocks for holding the sign-plates at a certain distance apart in each series, superposed shelves and endless chains arranged adjacent thereto and coöperating to support the series of signs and each shelf independently exposing one of the signs in each series, oscillating levers having an arm at each end engaging the signs supported by the chains to shift a sign onto each of the shelves and from each shelf another sign back onto said chains, a shaft having crank-arms for actuating said levers, a second shaft having sprocket-wheels for actuating said chains and means for actuating each of said shafts successively and independently of each other.

In testimony whereof I have hereunto set my signature in the presence of two subscribing witnesses.

ERNEST O. POHL.
